UNITED STATES PATENT OFFICE.

THEODORE P. BROWN, OF WORCESTER, MASSACHUSETTS, ASSIGNOR TO SIMPLEX
PLAYER ACTION COMPANY, A CORPORATION OF MASSACHUSETTS.

FOLDING PEDALS FOR PNEUMATIC MUSICAL INSTRUMENTS.

1,103,480.

Specification of Letters Patent.

Patented July 14, 1914.

Application filed March 22, 1913. Serial No. 756,077.

To all whom it may concern:

Be it known that I, THEODORE P. BROWN, a citizen of the United States, residing at Worcester, in the county of Worcester and 5 State of Massachusetts, have invented new and useful Folding Pedals for Pneumatic Musical Instruments, of which the following is a specification.

The principal objects of this invention are 10 to provide a pedal construction in which the pedals can move back into the casing through the ordinary low standard opening, and at the same time to avoid folding them back between the bellows so that in the de- 15 sign of the instrument there will be no re- striction as to the width of the elbows or pedals or their distance apart; also to pro- vide a construction of this character in which instead of doubling back and forth 20 in the case the pedals will move up into the case with a continuous motion and without making any sudden change in the direction of motion, whereby they will not have a tendency to deliver a blow to the rests on 25 which they strike in the casing.

The invention also involves improvements in details of construction and combinations of parts as will appear hereinafter.

Reference is to be had to the accompany- 30 ing drawings in which,

Figure 1 is a front elevation of the bellows, pedals and some connected parts of a pneumatic musical instrument constructed in accordance with this invention, the casing 35 being removed; Fig. 2 is an end elevation of the same showing the pedals in position for playing; and Fig. 3 is a similar view showing the pedals moved back within the casing.

40 In this case a pair of supports 10 at the bottom of the casing 9 are provided with bearings 11 for the ends of a shaft 12. This shaft has arms 13 connected at their ends by a cross member 14 on which are pivoted 45 the bottoms of the pedals 15. Supports 16 are mounted below as is usual in this class of devices. These supports are held from turning by screws 17.

At the upper end each of the pedals is 50 provided with a bracket 20 having a stud 21 thereon parallel with the shaft 12, and on this stud is pivoted the head of a hollow rod 22. Inside this hollow rod projects a second rod 23 pivoted at its inner end to the

movable leaf of the bellows 24. These two 55 rods constitute a telescoping connection.

On the front or edge of the bellows are located runs or guides, shown as springs 26, extending downwardly along the bellows at their inner edges and projecting out for- 60 wardly from them at the bottom. They are secured to the bellows at the top. A pair of stationary cleats 27 are located on the bellows to cover the guides at a certain point. 65

The operation is very simple. Referring to Fig. 2, it will be seen that the rod 23 extends in substantially to the end of the opening in the rod 22; consequently when the operator presses on the pedals, the force 70 exerted is transmitted directly and without change of direction to the bottom of the movable leaf of the bellows and yet no springs, pivots, or other connections are required between the two rods 22 and 23. 75 When it is desired to move the pedals back into the case they are simply turned directly back through the usual standard opening and then upwardly within the instrument. On the way in the outer edge of each pedal 80 strikes the top of the run or guide 26. This cushions the blow, prevents the pedal fold- ing down as is usually the case, and causes it to move up along the run or guide, with- out reversing its position, until it reaches 85 the position shown in Fig. 3. Here the top of the pedal comes under the cleat 27, so as to be held from accidental displacement, and the bottom of the pedal engages the spring or guide again, thus cushioning the 90 blow if the pedals are moved back with un- due force. This action of course takes place without exerting any pressure on the mov- able leaf of the bellows or its spring, and the parts are turned over to such position 95 that there is no force tending to swing the pedals out to the front. The member 14 is prevented from swinging back farther from the position shown in Fig. 3 by the back of the lower end of the pedal coming into con- 100 tact with the screw 17, if the spring 26 does not keep it out of contact therewith.

It will be seen that by this construction, a number of joints usually employed are eliminated and consequently the expense of 105 manufacture and assemblage, as well as re- pairs is reduced. Moreover, the pedals are left, when moved back in the instrument, in

a position from which they are adapted to fall down by gravity upon being turned forwardly a very slight distance and it is not necessary, under any conditions, to reach far 5 into the instrument for the purpose of moving the pedals out. Moreover, the pedals can be made wider than is now the case, and the bellows can also be made wider or spaced nearer together.

10 Although I have illustrated and described only one embodiment of the invention, I am aware of the fact that the invention can be carried out in many other forms without departing from the scope thereof as expressed 15 in the claims. Therefore, I do not wish to be limited in these respects, but what I do claim is:—

1. In a musical instrument, the combination of a pedal, a swinging support for the 20 bottom thereof, a bellows, and two rods connected with the movable leaf of the bellows and with the pedal respectively, one rod being hollow and the other extending freely 25 into the hollow rod and to the end thereof when the pedal is in operative position, whereby the pedal can be swung up without exerting any force on the bellows.

2. In a musical instrument, the combination of a pedal, a swinging support for the 30 bottom thereof, a hollow rod pivoted to the

upper end of said pedal, a bellows, and a rod pivoted to the movable leaf of the bellows and extending freely and loosely into said hollow rod for transmitting motion from the pedal to the bellows.

35

3. In a musical instrument, the combination of a pedal, a swinging support for the bottom thereof, a bellows behind the pedal connected with the upper end thereof, and a resilient yielding guide on the front of said 40 bellows for receiving the top of the pedal when swung rearwardly on said support.

4. In a musical instrument, the combination of a pedal, a swinging support for the bottom thereof, a bellows behind the pedal 45 connected with the upper end thereof, a guide on the front of said bellows for receiving the top of the pedal when swung rearwardly on said support, and guiding the end of the pedal upwardly along the front 50 bellows, and a cleat on the bellows for holding the end of the pedal.

In testimony whereof I have hereunto set my hand, in the presence of two subscribing witnesses.

THEODORE P. BROWN.
